UNITED STATES PATENT OFFICE.

SIGMUND FREY, OF LOS ANGELES, CALIFORNIA, ASSIGNOR TO WOOLWINE METAL PRODUCTS COMPANY, OF LOS ANGELES, CALIFORNIA, A CORPORATION OF CALIFORNIA.

CANTEEN-HOLDER.

1,382,969.

Specification of Letters Patent. Patented June 28, 1921.

Application filed April 5, 1920. Serial No. 371,517.

To all whom it may concern:

Be it known that I, SIGMUND FREY, a citizen of the United States, residing at Los Angeles, in the county of Los Angeles and 5 State of California, have invented a new and useful Canteen-Holder, of which the following is a specification.

This invention relates to a device for holding a canteen or series of canteens in 10 place on the running board of a motor vehicle, and an object of the invention is to provide a device of this character of comparative simplicity of construction and operation.

15 Another object is to make provision in a holder of this description for preventing looseness and consequent rattling of the canteens in the holder when the motor vehicle is running.

20 Another object is to make provision for firmly holding the canteens, even though said canteens may be of slightly different diameters.

Another object is to provide a holder having a neat appearance.

Other objects and advantages will appear hereinafter.

The accompanying drawings illustrate the invention.

30 Figure 1 is side elevation of a motor car equipped with a canteen holder embodying the invention, a set of canteens being shown in place in the holder.

Fig. 2 is an enlarged end elevation of the 35 canteen holder from line indicated by x^2 , Fig. 1, the running board being shown in section. Solid lines show the parts in closed position, and dotted lines indicate the movable members in open position for insertion 40 or withdrawal of the canteens.

Fig. 3 is a broken plan view partly in section on line indicated by x^3-x^3 , Fig. 2.

Fig. 4 is a side elevation from the right of Fig. 2, the attaching members being 45 shown in section.

Fig. 5 is a fragmental side elevation, partly in section on line indicated by x^5-x^5 , Fig. 2.

There are provided attaching members 1 50 adapted to extend transversely of and rest upon the running board 2 of a motor car, indicated in general by the character 3 in Fig. 1. At one end the attaching members 1 are bent downwardly and inwardly to 55 form U-shape portions 4 adapted to extend

beneath the outer edge of the running board as clearly shown in Fig. 2. The bent-under ends of the U-shape members 4 are provided with clamping means 5 in the form of screws adapted to engage the under faces of the 60 running board to secure the holder in place. In the instance shown in the drawings the attaching members 1 are channel shape in cross section, and projecting upwardly from each member 1 is a pair of crossed 65 members 6, 7. The lower ends of the members 6, 7 rest in the channels and are secured to the members 1 by rivets 8 or their equivalents. The members 6 are secured to the members 7 by rivets 9 or their equivalents. In the particular instance shown the members 6, 7 are arranged substantially at right angles to each other and the members 6 are somewhat shorter than the members 7, 70 though this is not absolutely essential.

The upper ends of the members 7 are connected to each other by a cross bar 10 and, in this instance, the members 7 and cross bar 10 together constitute an inverted U-shape member. Pivoted at 11 to the members 7, between the rivets 9 and the members 1, are movable arms 12 which are connected to each other at their outer ends by a cross bar 13, the arms 12 and cross bar together constituting an inverted U shape member. 80 Pivoted at 14 to the arms 12 are latch members 15, and the members 6 and arms 12 are positioned in coinciding planes so that the latch members 15 will engage the outer faces of the members 6, when the arms are in the 85 raised position shown in Fig. 2. The latch members 15 are provided with hooks 16 adapted to lock over the upper edges of the members 6 so as to hold the cross bar 13 toward the cross bar 10. When the latch 90 members 15 are in latching position, their upper ends project above the members 6 so as to form operating handles 17.

The canteens, which are indicated at 18 in Fig. 1, are adapted to be held between the 100 cross bars 10, 13 and, if desired, any looseness of fit between the canteens and the cross bars 10, 13 may be taken up by resilient pads 19 fixed to the cross bar 10 and formed of rubber or other suitable yielding material. The pads 19 are preferably held by clips 20 which slidably engage the cross bar 10 so that the pads may be shifted from one position to another to meet the various requirements occurring in practice. The pads 105 110

19 project from the inner face of the cross bar 10 so as to engage the peripheral walls of the canteens.

When the canteens 18 are in place in the holder they rest upon and are supported by the running board 2, and the cross bar 13 and cross bar 10 or pads 19, if said pads are used, engage the peripheral walls of the canteens. The cross bar 13 holds the canteens 10 toward the cross bar 10 and toward the running board 2.

In practice, assuming that the canteens are in place in the holder as in Fig. 1, the latch members 15 will be swung upwardly and outwardly to disengage the hooks 16 from the members 6. Then the arms 12 and cross bar 13 will be swung outwardly and downwardly from the position shown in solid lines in Fig. 2 to the position shown in 20 broken lines *a*, thus releasing the canteens. When the arms 12 are in full open position they rest within the channel member 1, which thus form stops for said arms. When the arms 12 are in the open position *a* the 25 canteens are readily removed and replaced by moving them away from or toward the cross bar 10.

It is understood that the term "canteens," employed in this specification, defines any 30 suitable container of the character employed in carrying water, oil, fluid fuels and the like. The holder may be made of any length capable of accommodating the number of canteens which it is desired to carry on the 35 motor car.

From the foregoing it is clear that the holder is of comparatively simple construction; that it can be quickly opened and closed; that when open the canteens can be 40 quickly and easily removed from and placed in the holder; and that when closed the canteens will be securely held against movement. Because of the provision of the pads 19 not even rattling of the canteens can 45 occur.

It is to be understood that the invention is not limited in scope by the exact details of construction disclosed in the drawings and described above, but that the invention

also includes such changes and modifications 50 as may be made without departing from the spirit of the invention as defined in the appended claims.

I claim:

1. In a canteen holder, attaching members, 55 an inverted U-shape member fastened to the attaching members, a second U-shape member pivotally connected to the first U-shape member, and a latch between the U-shape members to hold the second U-shape member 60 against movement away from the first U-shape member.

2. In a canteen holder, opposed members adapted to hold a canteen between them, 65 means to attach said members to a support, one of said members being movable and the other stationary, and latch means between the opposed members to hold the movable member against movement away from the stationary member. 70

3. In a canteen holder, attaching members, opposed members adapted to hold a canteen interposed therebetween, one of said opposed members being movable toward and from the other member, releasable means to hold the movable member against movement away from said other opposed member, and one of the opposed members being provided with a yielding member to engage the canteen. 75

4. In a canteen holder, attaching members, 80 means to fasten the attaching members transversely of the running board of a motor vehicle, crossed end members having their lower ends fastened to the attaching members, a cross member connecting one of the 85 end members at one end to one of the end members at the opposite end, arms pivoted to the last named end members, a cross member connecting the arms to each other, and means on the arms coöperating with the 90 other end members to hold the arms against outward movement.

Signed at Los Angeles, California, this 26th day of March, 1920.

SIGMUND FREY.

Witnesses:

GEORGE H. HILES,
L. BELLE WEAVER.
